AUTOMATIC TELEPHONE SYSTEM

John H. Voss, Downers Grove, and Harry N. Newstedt, Chicago, Ill., assignors to Associated Electric Laboratories, Inc., Chicago, Ill., a corporation of Delaware

Application September 5, 1933, Serial No. 688,102

22 Claims. (Cl. 179—18)

This invention relates to automatic telephone systems in general, but relates more particularly to small systems of the character commonly known as private automatic exchanges. These systems as a rule are privately owned by individuals or corporations and are installed in factories and other establishments for providing local service between a small number of local telephone lines and for providing connections over trunk lines to the main office of a telephone company's network.

The object of the invention is to provide means whereby a minimum number of switching devices will be employed for completing the desired telephone connections, and which will enable the equipment to be manufactured very cheaply while retaining all the features necessary for modern high-class and dependable telephone service.

One of the features of the invention relates to the means for enabling local subscribers to transfer trunk connections to desired local subscribers' lines and at the same time maintain the trunk in use busy to the remaining other local subscribers' lines.

Another feature relates to the simplified circuit arrangements for enabling any local subscriber to connect with an idle trunk after which such trunk is made busy to the remaining local subscribers' lines.

A further feature of the invention relates to the provision of a two-relay allotter which alternately selects the two finder connector links for use and which also seizes the idle one of the links in case the other link normally selected by the allotter is busy when a call is initiated.

Other features, together with the ones named above, will be explained hereinafter, reference being had to the accompanying drawings comprising Figs. 1 and 2 which show by means of the usual circuit diagrams a sufficient amount of apparatus to enable the invention to be understood.

Fig. 1 illustrates a local subscriber's line and its individual equipment, the common start equipment and two trunks connected to a distant central office.

Fig. 2 illustrates a finder connector link comprising the finder F, the connector C, and the interposed relay group, and a local subscriber's line indicated by the dotted rectangle in the upper right hand corner.

Referring now to Fig. 1 in detail, all subscribers, such as subscriber #5, are equipped with a standard and well-known monophone set. Each set comprises a handset T and R, a calling de-

vice CD, a cradle and cradle spring CS, an induction coil IC, and the ringer bells RB. Each line has a local line circuit, the conductors of which terminate in the local finder and connector banks for completing local calls. Attached to the base of each standard monophone set is a sub-base having a number of spring assemblies and keys which are operated when originating or receiving trunk calls. Each sub-base has two keys TK-1 and TK-2 for originating and answering trunk calls. A push button PB is also provided in the sub-base for flashing an operator in a trunk call to a manual exchange or for cancelling the digits dialled if an error has been made in dialling an automatic subscriber in either the local or a distant automatic exchange. Conductors extending from the spring assemblies controlled by these keys extend to the subscribers' individual trunk relays 60 and 70 and from thence to the two central office trunks 1 and 2. The conductors 81 to 86, inclusive, are multiplied to all the subscribers' individual trunk relays 60 and 70 as indicated in Fig. 1 and by those conductors shown extending to the dotted rectangle in Fig. 2. Each trunk is provided with a pair of relays, different toned ringers, such as TR1 and TR2, or alternating current relays such as 88 and 87 which control circuits for illuminating the different colored trunk lamps. The different colored lamps or different toned ringers are located throughout the local establishment where the same are visible or audible to all the local subscribers. All local subscribers' lines have an individual cut-off relay, such as relays 4 and 184, and all lines terminate in both the finder and connector banks shown in Fig. 2. Relay 8 is a line relay common to all the subscribers' lines and controls the start circuit for the finder connector banks through the two-relay allotter comprising relays 10 and 11.

The mechanical construction of the spring assemblies and keys in the sub-bases is shown and claimed in a copending application of H. F. Obergfell, Ser. No. 536,424, filed May 11, 1931. Briefly the operation is as follows: When the handset is removed from the cradle, springs 53 and 54 automatically close. If either key TK-1 or TK-2 is depressed, the bar 47 slides in a horizontal direction and by means of bushings 48, 49 and 50 operates springs 51, 52, 56, and 58. Springs 55 are operated only when trunk key TK-2 is depressed. A mechanical lock (not shown) is provided for preventing either key from being operated when the other is operated. The catch bar 57 is operated responsive to the

removal of the handset from the cradle to position itself so that when springs 52 and 55 are operated the same will be mechanically locked until the handset is replaced on the cradle irrespective of the subsequent operations of the keys. The keys TK-1 and TK-2 are keys or levers which are moved off center and remain in such positions until moved by hand back to normal or until the handset is replaced on the cradle, which 10 automatically returns the keys to their normal positions. The push-button PB is of the self-restoring type and operates springs 46 only as long as the push-button is depressed.

The mechanism of the finders, such as F, and 15 the connectors, such as C, is of the well-known rotary type, commonly used for rotary line-switches, and the wipers of which move in a forward direction only and remain in the position last used. The circuit details of the connector are somewhat different from the finders in that the wipers of the connector are directly operated to a called line and are automatically restored to normal position after termination of the conversation.

25 In the case illustrated applicant has elected to show a system having a maximum of ten local lines having telephone numbers 1 to 0, inclusive, and two finder connector links, such as shown in Fig. 2.

30 The subscribers' cut-off relays, such as 4 and 184, and relay 140, are two-step relays which close their contacts marked I in their first step and their contacts marked II in their second step. Relay 120 is a slow-to-operate relay which 35 is also appreciably slow to release. Relays 130 and 180 are equipped with copper sleeves around their cores which render the relays slow to release.

Local connection

40 Having briefly described the apparatus involved in a system of this type, a detailed description of the operation will now be given. For this purpose, it will be assumed that subscriber #5 wishes 45 to obtain connection with subscriber #4. When subscriber #5 removes his handset to initiate a call, a circuit is completed for the common line relay 8 and cut-off relay 4 as follows: from ground through relay 8, common conductor 3, armature 5, conductor 31, resting contact of spring 56 and said spring, push-button springs 46, conductor 1, through the calling substation loop, conductor 2, spring 51 and its resting contact, conductor 32, armature 7, and through the 55 upper winding of cut-off relay 4 to battery. Cut-off relay 4 is so adjusted that when the circuit is closed through the upper winding armature 6 is the only armature operated. Relay 4 in operating its armature 6 marks the line as calling 60 by connecting battery through its lower winding to the finder bank, and prepares a circuit for fully energizing itself over its lower winding when the finder finds the calling line. Common line relay 8 is operated over the above traced 65 circuit and closes a circuit for a start relay of an idle finder-connector link as follows: ground by way of armature 9, armature 12 and its resting contact, upper winding of relay 11, start lead 16, winding of slow-to-operate start relay 70 120, armature 145 normal position or eleventh bank contact and wiper 108, interrupter springs 136 of the connector motor magnet 135, armature 197, and through the winding of magnet 135, to battery. Due to the resistances of relays 11 and 120 the motor magnet 135 is not energized

over this circuit, but relay 11 and start relay 120 energize. Since the start relays of the finder-connector links are slow to operate relays, relay 11 operates first and opens the start circuit to the second finder connector link at armature 14 5 before the start relay 120' of the second link has had time to fully operate.

In case this finder-connector link is busy, then armature 145 would be opened and the wiper 108 would not be in normal position; therefore no 10 circuit is completed for relays 11 and 120 and the start circuit would extend to the second finder-connector link by way of armature 14 and conductor 16' to start relay 120' and over a circuit similar to that traced, to battery. In case 15 all of the finder-connector links are busy when a subscriber initiates a call such subscriber will not hear the dial tone and will either wait until dial tone is heard or will replace the handset on the cradle. 20

Returning now to when start relay 120 was energized in response to subscriber #5 initiating a call, said relay at armature 121 prepares the test circuit for relays 140 and 150, at armature 122 prepares a point in the circuit for energizing 25 relay 10 over conductor 17, at armature 124 prepares a circuit for relay 150, and at armature 123 closes a circuit extending from ground at armature 151 and its resting contact for energizing the finder motor magnet 125. Magnet 125 30 energizes to position its pawl preparatory to stepping the wipers of the finder and near the end of its stroke closes armature 126 to complete a circuit for energizing relay 150 by way of armature 124 and its lower winding. Relay 150 energizes and at armature 151 opens the circuit 35 extending to magnet 125 which deenergizes and operates the wipers of the finder one step. The deenergization of magnet 125 also opens the circuit of relay 150 at armature 126, and the latter 40 relay deenergizes to again close the circuit to the motor magnet. This interaction between relay 150 and magnet 125 continues until test wiper 102 encounters a calling battery potential. When wiper 102 reaches the contact marked with calling battery potential a circuit may be traced for holding relay 150 energized and for energizing relay 140 as follows: from ground by way of the upper winding of relay 150, normally closed 45 springs controlled by armature 141, lower winding of two-step relay 140, armature 121, test wiper 102 and engaged bank contact, conductor 33, armature 6 and through the lower winding of cut-off relay 4, to battery. The relay 150 is held energized over this circuit in order to prevent the 50 magnet 125 from energizing to step the wipers another step. Cut-off relay 4 energizes in its second step over the above-traced circuit. Two-step relay 140 energizes in its first step over the 55 above-traced circuit to close only armature 143, which completes a circuit for energizing slow-to-release relay 130 by way of the working contact of armature 151. Slow-to-release relay 130 at armature 132 connects ground to conductor 17 by way of armature 122 for energizing relay 10 and 60 also connects ground through the upper winding of relay 140 for energizing the latter relay through its second step to operate armatures 141, 142, 144, and 145, at armature 134 prepares a point in the talking circuit as well as preparing 65 a point in the impulsing circuit for relay 150, at armature 144 prepares a circuit for series relay 180 and a circuit for the connector motor magnet 135, and at armature 131 and its resting contact 70 opens a point in the wiper restoring circuit 75

for the connector and at its working contact prepares a point in the testing circuit for the connector. At the normally closed springs controlled by armature 141 relay 140 opens the test circuit including the windings of relay 140 and 150, but these relays do not deenergize at this time because relay 140 is held over its upper winding while the subscriber's calling loop is now connected in bridge of both windings of relay 150 to prevent its deenergization. At armature 142 relay 140 grounds wiper 102 and conductor 33 to fully energize cut-off relay 4 in its second step and to make this line busy to both finder and connector switches and at armature 144 prepares a point in the circuit for the slow-to-release series relay 180. At armature 145 relay 140 opens the circuit of start relay 120, which deenergizes after a short interval to open the start circuit. Relay 120, upon deenergizing, at armature 123 opens the circuit to the finder magnet 125, at armature 121 opens the circuit to the lower winding of relay 140, at armature 122 removes ground from conductor 17 but relay 10 is maintained energized over its local locking circuit, and at armature 124 opens the stepping circuit to the lower winding of relay 150. Cut-off relay 4, upon energizing in its second step, disconnects the line conductors 31 and 32 from the upper winding of relay 4 and from common line relay 8, which deenergizes in case no other subscriber is initiating a call. When conductor 17 is grounded at armature 32 responsive to the energization of relay 130 relay 10 energizes through the normally closed springs controlled by armature 13 to battery through resistance 18. At armature 13 relay 10 closes a local locking circuit for itself and at armature 12 prepares the start circuit for the second finder connector link.

All of the operations just described have taken place responsive to the #5 subscriber removing his handset from the cradle, and at this time dial tone is transmitted from conductor 129, normal contact and wiper 106, resting contact of armature 161 and said armature, the tone condenser, and thence over the calling subscriber's loop in the well-known manner.

Subscriber #5 may now dial the number of the desired subscriber's line, in this case number 4. Responsive to the operation of the calling device CD at substation #5 for the digit 4, the circuit extending to relay 150 is opened four times to deenergize relay 150 a corresponding number of times. At each deenergization of relay 150 the circuit of slow-to-release relay 130 is momentarily opened at armature 151 and its working contact, but said relay, due to the copper sleeve around its relay core, maintains its armatures attracted during the impulsive period. Each time relay 150 deenergizes, a circuit may be traced from grounded armature 151 and its resting contact, armature 133, armature 163, armature 197, and through the winding of magnet 135 to battery for energizing magnet 135 to operate its pawl preparatory to stepping the wipers of the connector. A branch of the above-traced circuit extends by way of armature 144 to the series relay 180 for energizing the latter relay. Relay 180 at armature 181 and its resting contact opens a point in the circuit of switching relay 190 and at its working contact prepares a point in the circuit for the lower winding of the combined busy and back bridge relay 160, and at armature 182 prepares a new impulsive circuit for magnet 135 independent of armature 163 which may be operated by the combined busy

and back bridge relay 160 operating in response to the test wiper 107 passing over busy grounded contacts. After the first impulse line relay 150 reenergizes and opens the circuit of magnet 135 which releases and steps the wipers one step. The remaining impulses of the digit operate the line relay 150 and magnet 135 in the manner set forth to position the wipers 106 to 111, inclusive, on the fourth set of bank contacts, or the contacts terminating the line of substation #4. 10

Assuming that substation #4 is busy, then wiper 107 will encounter a ground connection on the fourth bank contact placed thereon by a finder or connector of another finder connector link. In this case the combined back ridge and busy relay 160 is energized over a circuit extending from the busy grounded contact, wiper 107, armature 181 and its working contact, armature 195, resistance 174, and through the lower winding of relay 160 to battery. Relay 160, upon energizing at armature 162 and its working contact prepares a locking circuit for itself, and at its resting contact opens the circuit to switching relay 190, at armature 163 opens a point in the initial impulsive circuit to magnet 135, and at 25 armature 161 completes a circuit for transmitting busy tone over the talking conductors to subscriber #5 from busy tone conductor 128, armature 192 and the tone condensers to the upper heavy talking conductor. 30

A short time after the transmission of the last digit, series relay 180 deenergizes, and at the normally closed contacts controlled by armature 181 completes the locking circuit of relay 160 as follows: from grounded armature 193, armature 131 and its working contact, armature 162 and its working contact, normally closed springs controlled by armature 181, and through the resistance 174 and the lower winding of relay 160 to battery. When subscriber #5 hears the busy 40 tone such subscriber will replace the handset on the cradle and release the connection in the same manner as will be described hereinafter.

Assuming now that substation #4 is idle instead of busy, then wiper 107 will not encounter a 45 grounded bank contact, and, therefore, relay 160 will not be energized. Therefore, when relay 180 deenergizes after the impulsive period, a circuit may be traced for energizing switching relay 190 and cut-off relay 184 as follows: from grounded 50 armature 193, armature 131 and its working contact, armature 162 and its resting contact, lower winding of switching relay 190, resting contact of armature 181 and said armature, wiper 107, and through the upper winding of cut-off relay 184, 55 to battery.

Cut-off relay 184 is operated over this circuit to operate its armatures 185 and 187 to disconnect the line conductors 166 and 168 from start conductor 3 and the lower winding of relay 184, and 60 to operate armature 186 to apply ground to conductor 167 via the bank contact and wiper 107 and operated armature 194 to busy this line in the finder banks. At armature 196 relay 190 closes a circuit from grounded armature 132 through its 65 upper winding for fully operating its remaining armatures. Relay 190, upon fully operating at armature 193 opens a point in the restoring circuit of the connector, at armature 192 opens a point in the busy tone circuit, at armature 194 70 connects direct ground to wiper 107 to busy the called line, at armature 195 opens a point in the circuit through the lower winding of relay 160, at armatures 198 and 199 prepares circuits for transferring trunk calls, at armature 191 opens a 75

point in the impulsing circuit to magnet 135, and at armatures 191 and 189 connects interrupted generator Int. Gen. to the called line as follows: from interrupted generator conductor 127, armature 171 and its resting contact, armature 191, wiper 106 and engaged bank contact, conductor 168, condenser and ringer at substation #4, conductor 166, wiper 111, armature 189, armature 173 and its resting contact, and through the lower winding of ring-cut-off relay 170 to battery.

Standard ring-back tone is heard by the calling subscriber from conductor 127, resting contact of armature 171 and said armature, armature 191, resting contact of armature 161 and said 15 armature, and through the tone condensers to the heavy talking conductor and thence over the calling loop. When subscriber #4 answers by removing his handset from the cradle, the ring-cut-off relay 170 is energized over the substation loop 20 and the ringing circuit just traced. At armatures 171 and 173, relay 170 disconnects the ringing circuit and completes the talking circuit by way of the working contacts of armatures 171 and 173 as well as completing the circuit for energizing relay 25 160, and at armature 172 completes a locking circuit for itself to grounded armature 132. The circuit for energizing the combined back bridge and busy relay 160 extends from ground through the upper winding of relay 160, working contact 30 and armature 171, armature 191, wiper 106, conductor 168 over the called subscriber's loop to conductor 166, wiper 111, armature 189, armature 173 and working contact, and through the lower winding of relay 160 to battery. At armatures 35 164 and 165 relay 160 closes points in the circuits for transferring trunk calls. The calling subscriber #5 and called subscriber #4 are connected over the heavy talking conductors, the calling subscriber receiving talking battery from 40 the windings of line relay 150 and the called subscriber receiving talking battery from the winding of relay 160.

After conversation and responsive to subscribers #5 and #4 replacing their receivers, line relay 150 and relay 160 deenergize and at armature 151 relay 150 opens the circuit of release relay 130, which deenergizes after a short interval. At armature 132 release relay 130 opens the locking circuits of relays 140, 170 and 190, and at armature 131 45 opens the locking circuit of relay 160 in case the latter relay is locked up on a busy call, whereupon said relays deenergize. A circuit may now be traced for restoring the wipers of the connector to normal as follows: from grounded armature 50 193, armature 131 and its resting contact, multiplied contacts engaged by wiper 108 and said wiper, interrupter springs 136 of magnet 135 and through the winding of magnet 135 to battery. Magnet 135 operates like a buzzer over the above-traced circuit until wiper 108 no longer engages a grounded contact, at which time the wipers of the connector stop and remain in normal position or the position shown in the drawings.

The deenergization of relay 140 removes ground 55 from wiper 102 and conductor 33 to deenergize the cut-off relay 4 at armature 142 and at armature 145 reestablishes the start circuit for relay 120. The deenergization of relay 170 at armatures 171 and 173 disconnects the relay 160 from 60 the called line to deenergize the same in case the called party has not replaced his handset on the cradle. The deenergization of relay 160 opens points in the transfer circuits at armatures 164 and 165. The deenergization of relay 190 opens 70 75 the circuits to the called line at armatures 191

and 189, at armatures 193 and 197 closes the previously traced connector restoring circuit, at armatures 198 and 199 opens further points in the transfer circuits, and at armature 194 disconnects ground from wiper 107 to deenergize cut-off relay 184. All of the relays with the exception of relay 10 are now deenergized and in normal position. The wipers of the finders remain in the positions last used, and, therefore, when the connector wipers reach their normal positions the finder- 10 connector link is available for another call.

Incoming trunk calls

It will now be assumed that an incoming trunk call is received over conductors 90 and 91 from 15 the distant office. When an incoming trunk call is received the application of ringing current to trunk conductors operates either the ringers TR-2 or the alternating current relay 81 dependent upon which is provided. Relay 81 at its 20 armature closes the circuit from the commercial power source for lighting the trunk #2 red trunk lamps located throughout the establishment. Any subscriber upon observing the lighting of the trunk lamp may answer the call by operating 25 trunk key TK-2 and removing the handset from the cradle. Assuming that subscriber #5 answers this trunk call, the operation of key TK-2 springs 51, 52, 55 and 56 are operated and in response to the removal of the handset from the cradle springs 30 53 and 54 are closed as previously described. A circuit may now be traced for energizing relay 70 as follows: from grounded springs 55, normally closed springs controlled by armature 64, and through the upper winding of relay 70 to battery. 35 At armature 71 relay 70 disconnects the busy test conductor of trunk #1 at its resting contact and at its working contact connects up the busy test conductor of trunk #2 for energizing relay 60, at armatures 72 and 73 disconnects the talking conductors of trunk #1 and connects the talking conductors of trunk #2, at armature 74 completes a locking circuit through its lower winding from springs 55 independent of armature 64, and at armature 75 connects ground to conductor 20 for 40 transfer purposes. Relay 60 now energizes over the following circuit: from ground at the resting contact of armature 69 and said armature, working contact of armature 71 and said armature, resting contact of armature 61 and said armature, 45 working contacts of spring 51 and said spring, conductor 2, through the induction coil IC, upper cradle springs CS, transmitter T, impulse springs of the calling device CD, conductor 1, push button springs 46, spring 56 and its working spring 58, 55 armature 62 and its resting contact, and through the winding of relay 60 to battery. At armature 61 and its resting contact relay 60 opens its own original energizing circuit by disconnecting from the trunk busy test conductor and at its working 60 contact connects the trunk conductor 90 to the local subscriber's talking conductor 2 by way of armature 72 and spring 51. At armature 62 and its resting contact relay 60 opens another point in its own original energizing circuit and at its 65 working contact connects the trunk conductor 91 to the local subscriber's talking conductor 1 by way of armature 73, and springs 58, 56 and 46. At armature 63 relay 60 closes a locking circuit for itself from springs 53 before its original energizing circuit is opened, at armature 64 opens the original energizing circuit of relay 70 as well as completing a circuit through the upper winding of relay 70 from conductor 20 which is grounded at armature 75, and at armature 65 grounds con- 70 75

ductor 21 for transfer purposes. The subscriber's substation loop is now bridged across the trunk conductors 90 and 91 and automatically causes the disconnection of ringing current from the central office in the well known manner. Since relay 66 is connected in series with trunk conductor 90 said relay now energizes from battery at the central office and at armature 68 completes a circuit for energizing busy relay 67. At armature 69 and its resting contact relay 67 disconnects ground from the trunk busy test conductor 86 to prevent any other local subscriber from seizing this trunk and at its working contact connects the busy tone conductor 128 to conductor 86 to give another subscriber, attempting to take this trunk into use, a busy tone.

In case another subscriber should attempt to take this trunk line into use by the operation of key TK-2 to answer this trunk call or to originate a trunk call, such subscriber will hear the busy tone. For example, assuming trunk line 2 is busy, then relay 67 is energized to disconnect ground from conductor 86 and connects busy tone in place thereof. Therefore, when the key TK-2 is operated, the relay such as relay 70 is operated but no circuit is completed for the trunk connecting relay such as 60 because ground is removed from conductor 86 with the result that the calling local subscriber in this case is not connected to trunk 2 and hears the busy tone to inform him that the trunk is busy.

Returning now to the connection of subscriber #5 to trunk #2, the subscribers receive talking battery from the central office and talk over the heavy talking conductors. After conversation and in response to the replacement of the handset on the cradle the key TK-2 and spring assemblies are automatically restored to normal position at which time springs 51, 52, 55, 56, 58 and 59 are in the position shown in the drawings, while springs 53 and 54 are now open since the handset has been replaced. Cradle springs CS and springs 51 and 56 open the talking circuit to the trunk and relay 66 and latter relay 67 deenergize. At armature 69 relay 67 disconnects the busy tone from conductor 86 and connects ground in place thereof to enable any local subscriber to seize this trunk in originating or answering a trunk call. Springs 53 open the locking circuit of relay 60 which now deenergizes and disconnects the trunk conductors from the local subscriber's spring assembly as well as opening the circuit through the upper winding of relay 70. Relay 70 likewise deenergizes because its locking circuit through its lower winding is opened at springs 55 while the circuit through its upper winding is opened at armature 64. The local subscriber's individual equipment including the spring assemblies and the trunk relays are now in normal position.

Since trunk #1 is identical to trunk #2 the local subscribers are signalled in a similar manner and any local subscriber may answer an incoming call over trunk #1 by operating key TK-1 and removing the handset from the cradle. The operation of key TK-1 operates all the spring assemblies as described for TK-2 with the exception of spring 55 and therefore no circuit is completed for relay 70. In this case relay 60 is energized over the following circuit: from ground by way of resting contact of armature 79 and said armature, trunk busy test conductor 82, resting contact of armature 71 and said armature, resting contact of armature 61 and said armature, springs 51 and its working contact, over the subscriber's

loop to springs 56 and 58, armature 62 and its resting contact, and through the winding of relay 60 to battery. At armature 61 relay 60 disconnects from the trunk busying conductor 81 and connects up to the trunk conductor 92, at armature 62 opens the original energizing circuit of relay 60 and connects up to the trunk conductor 93, at armature 63 completes a locking circuit for itself from grounded springs 53 as well as grounding conductor 22, at armature 64 opens the circuit to relay 70 to prevent its energization, and at armature 65 grounds conductor 21 for transfer purposes. In a manner similar to that previously described the local subscriber's line loop is connected over the heavy talking conductors to the trunk conductors 92 and 93 and relays 76 and 77 energize; relay 77 removing ground from conductor 82 to prevent any other local subscriber seizing this trunk and placing the busy tone on a conductor 82 to give the busy tone to any local subscriber attempting to thereafter seize the trunk. It being understood that the removal of ground from conductor 82 prevents the energization of the local subscriber's individual trunking connecting relay, such as relay 60. The release of a connection over trunk #1 after conversation is similar to that described for trunk #2.

Outgoing trunk calls

It will now be assumed that subscriber #5 desires to originate a call to a subscriber in the central office, and will therefore remove the handset from the cradle and operate trunk TK-1. In response thereto springs 53 and 54 close and springs 51, 52, and 56 are operated. In case trunk #1 is busy the subscriber will hear the busy tone over the following circuit: from busy tone conductor 128, armature 79, conductor 82, resting contacts of armatures 71 and 61 and said armatures, working contact and spring 51 over the subscriber's loop to springs 56 and 58, armature 62 and resting contact and to battery through relay 60. Relay 60 does not energize over this circuit and therefore the subscriber is not connected to trunk #1. After hearing the busy tone the subscriber will release the key TK-1 and operate key TK-2 to close the same spring assemblies as TK-1 and also to close springs 55 to energize relay 70 over the circuit previously traced. Relay 70 disconnects trunk #1 and prepares trunk #2 for connection. In case trunk #2 is busy the subscriber will hear the busy tone over a circuit including armature 69 and its working contact, conductor 86, working contact and armature 71, and thence over the subscriber's loop as previously described. The subscriber will now replace his handset and release the key TK-2 and relay 70 and wait for an interval before calling.

In case the trunk #1 is idle when the subscriber operated key TK-1 to originate an outgoing call a circuit may then be traced for energizing relay 60 as follows: from ground at resting contact of armature 79, conductor 92, resting contacts of armature 71 and 61, spring 51, over the calling subscriber's loop, springs 56 and 58, armature 62 and resting contact, and through relay 60 to battery. Relay 60 energizes and locks connecting the local subscriber to trunk #1 and relays 76 and 77 energize as previously described. In case trunk #1 extends to a manual exchange the operator will answer and complete the call and in case the trunk extends to an automatic exchange the local subscriber waits for dial tone and then operates the calling device CD in ac-

cordance with the distant called subscriber's number to operate switches at the central office to complete the connection.

In a similar manner in case trunk #2 is idle 5 when the subscriber operated key TK-2 to originate an outgoing call relay 10 energizes from grounded spring 55 by way of the normally closed springs controlled by armature 64 and locks as previously described. Relay 60 now energizes 10 from ground at armature 69, by way of conductor 86, working contact and armature 71, and over the circuit previously traced to battery through relay 60. The operation of relays 60 and 10 connects the calling subscriber to trunk #2 after 15 which the trunk calls are completed as previously described.

Holding circuit

Any local subscriber can hold a trunk call while 20 either making or answering a local call by restoring the operated trunk key to normal. The restoration of the trunk key without replacing the handset disconnects the local calling subscriber's loop from the trunk line and connects it to its local line and also closes a holding bridge for the trunk line. When the trunk key 25 is restored springs 51 and 56 are restored to normal, while spring 52 and spring 53 (in case TK-1 was operated) are held locked in operated position by catch 57. Spring 53 maintains relay 60 energized over its locking circuit and maintains conductor 22 grounded. In case TK-2 had been 30 operated then spring 55 maintains relay 10 energized and conductor 23 grounded. The holding circuit for either trunk may be traced from armature 72, working contact and armature 61, through the impedance coil, locked springs 52, springs 54, springs 59 and 58, armature 62 and its working contact to armature 73. As will be seen 35 springs 56, 58 and 59 are a make before break combination to insure the closing of the holding circuit before the trunk is disconnected from the subscriber's loop. The trunk connection is held over this holding circuit while the local subscriber either originates or answers a local call 40 and by the reoperation of the proper trunk key the local subscriber can return to the trunk and release the local connection. Since the busy trunk relays, such as 67 and 71, are maintained 45 energized while the trunk is being held the trunk is made busy to all other local subscribers' lines.

Transfer circuits

A local subscriber can transfer a trunk connection to any other local subscriber by releasing the trunk key thereby holding the trunk connection over the holding circuit and then connecting with the desired local subscriber over the local finder connector links. The transfer arrangement is designed so that only the called 55 local subscriber, after being called by the local subscriber holding the trunk connection, can connect with the held trunk line, while all the other subscribers' lines are unable to connect to the held trunk line. If desired both local subscribers may remain connected to the held trunk line and may also transfer the call to a third local subscriber.

It will now be assumed that local subscriber 70 #5 is connected in a trunk call to the central office over trunk #1 and that the central office subscriber desires to converse with another local subscriber for example subscriber #4. In order to transfer the call subscriber #5 restores the operated trunk key TK-1, thereby establishing the

holding circuit for trunk #1 as previously described. Since the local subscriber did not replace the handset, the subscriber's loop is connected to the local line conductors 31 and 32 to cause the energization of common line relay 8 and cut-off relay 4 in its first step as previously described. In the same manner as described for a local connection the finder F is operated to find the calling local line and the subscriber operates the connector C to connect with and ring 10 the called subscriber, in this case the subscriber #4. When the called subscriber answers the calling subscriber advises the subscriber #4 that such subscriber is wanted on a trunk connection over trunk #1. Relay 160 energizes when the 15 called subscriber answers and at armature 165 completes a circuit for energizing the trunk connecting relay which is individual to subscriber #4 and which corresponds to relay 60. This circuit extends from ground at armature 65 of relay 20 60 individual to subscriber #5 by way of conductor 21, fifth finder bank contact and wiper 104, armatures 165 and 199, connector wiper 110, conductor 22' and through the winding of the trunk connecting relay individual to subscriber 25 #4 to battery. The operation of this trunk connecting relay connects the talking conductors 81 and 85 of trunk #1 to the spring assemblies in the sub-base of subscriber #4 in a manner apparent from the similar spring assemblies and 30 sub-base shown in detail in Fig. 1. The trunk connecting relay, similar to relay 60, also completes its own locking circuit from ground at springs similar to springs 53 by way of the armature similar to armature 63. From the fore- 35 going it will be seen that subscriber #4 is prepared for connection with trunk #1 in response to the operation of the subscriber's individual trunk connecting relay while trunk #1 is still maintained busy to all the remaining local subscribers since no means is provided for energizing their individual trunk connecting relays. In order to pick up the trunk connection, subscriber 40 #4 will operate the trunk key for trunk #1 without replacing the handset to the cradle. Subscriber 45 #4 is now connected to trunk #1 over the trunk conductors 81 and 85, shown in Fig. 1, which are connected to conductors 81 and 85 shown in Fig. 2 and from thence through the armatures on the trunk connecting relays, similar 50 to relays 60 and 10, to the spring assemblies and subscriber's loop individual to the subscriber #4, similar to the spring assemblies and subscriber's loop shown in Fig. 1 individual to subscriber #5. Subscriber #5 will now reoperate key TK-1 and 55 reconnect with trunk #1. When the subscriber operates key TK-1 the finder connector link is restored to use in the same manner as previously described and may be used on subsequent calls. If desired subscriber #5 may remain connected 60 to trunk #1 along with subscriber #4 or may release from the connection by replacing the handset on the cradle. This operation releases the spring assemblies and opens the locking circuit of relay 60 which deenergizes. Subscriber 65 #5 cannot come back on the trunk connection unless subscriber #4 calls subscriber #5 locally while maintaining the trunk connection. The reason for this is apparent from the foregoing description because no circuit is provided for 70 energizing relay 60 when the trunk #1 is busy. Subscriber #4 may transfer the trunk connection to another local subscriber, if desired, in the same manner as just described.

It will now be assumed that subscriber #5 is 75

connected in a trunk connection over trunk #2 and that such subscriber desires to transfer the connection to subscriber #4. In this case in order to transfer the call, subscriber #5 restores 5 the key TK-2 thereby establishing the holding circuit for trunk #2 as previously described. Relay 60 remains locked in energized position over spring 53, and relay 70 remains locked in energized position from ground at armature 75, 10 armature 64 and its working contact, and through the upper winding of relay 70 to battery. The local connection to subscriber #4 is established over the finder connector link in the same manner as previously described and when subscriber 15 #4 answers relay 160 energizes and completes energizing circuits for both trunk connecting relays individual to subscriber #4 since both conductors 20 and 21 are grounded. The circuit for energizing the trunk connecting relay corresponding 20 to relay 70 may be traced as follows: from ground at armature 75, conductor 20, fifth finder bank and wiper 103, armatures 164 and 198, wiper 109 and fourth connector bank, conductor 23', through the normally closed springs controlled by the 25 armature, similar to armature 64, and through the upper winding of the trunk connecting relay, similar to relay 70, to battery. The circuit for energizing the trunk connecting relay, similar to relay 60, is the same as that previously described over conductors 21 and 22'. As will be noted, the trunk connecting relays, such as relay 60, are slow to operate and therefore the relays, such as 70, energize and prepare locking circuits for themselves before the relays, such as 30 relay 60, fully operate. When the trunk connecting relay similar to relay 60 fully operates and locks as previously described, such relay at the armature corresponding to armature 64 completes a locking circuit for the relay corresponding to 35 relay 70. This locking circuit is similar to the locking circuit for relay 70 shown in Fig. 1 which extends by way of armature 75, armature 64 and through the upper winding of relay 70. The operation of the trunk connecting relays individual 40 to subscriber #4 connects the talking conductors 83 and 84 of trunk #2 to the spring assemblies in the sub-base of subscriber #4 preparatory to connecting trunk #2 to subscriber #4. In order 45 to pick up the trunk connection, subscriber #4 will operate the trunk key for trunk #2 without replacing the handset. Subscriber #4 is now connected to trunk #2 over trunk conductors 83 and 84, shown in Figs. 1 and 2, through the operated armatures of the trunk connecting relays 50 to the spring assemblies and local line loop individual to subscriber #4. If desired subscriber #5 may reoperate key TK-2 and remain in the trunk connection with subscriber #4 or may release from the connection by replacing the handset on the cradle. The replacement of the handset on the cradle restores the spring assemblies to normal and causes the deenergization of relay 60 as previously described. At armature 64 relay 60 opens the locking circuit of relay 70 which now deenergizes. By the deenergization 55 of relays 60 and 70 trunk #2 is made busy to subscriber #5 and such subscriber cannot return to the trunk connection unless called locally by another subscriber while such other subscriber is holding the trunk connection. Subscriber #4 may transfer the trunk connection to other subscribers in the same manner as just described.

Allotter operation

75 A second local call by any local subscriber en-

ergizes the common line relay 8 over conductor 3 in a manner similar to that previously described. However, in this case since relay 10 is locked locally, a start circuit is now closed for start relay 120' of the second finder connector link. 5 This circuit may be traced as follows: from grounded armature 9, armature 12 and its working contact, through the lower winding of relay 11, conductor 16', winding of start relay 120', armature 145', normal bank contact and wiper 108' to battery through the winding of the connector motor magnet of the second finder connector link. A branch of this circuit may be traced from the working contact of armature 12, armature 15, through the upper winding of relay 11, armature 14, to conductor 16'. The two circuits traced through both lower and upper windings of relay 11 assist each other to quickly energize relay 11. Another circuit is also closed by way of armatures 9 and 12 by way of armature 20 15 and conductor 16 for the start relay 120 of the first finder connector link, but since start relay 120 is slow to operate relay 11 will operate its armature 15 to open the circuit to relay 120 before the same can fully operate. In response to 25 the operation of start relay 120' the finder of the second finder connector link is operated to find the calling line after which the connector of the link is directly operated to connect with the called line in a manner similar to that previously 30 described. When the finder finds the calling line the release relay in the second link, corresponding to relay 130, energizes and at armature 132' grounds conductor 17' by way of armature 122' to short circuit relay 10 thereby causing the latter 35 relay to deenergize. This short circuit extends from grounded conductor 17' through the winding of relay 10 to ground at armature 13. The calling subscriber's cut-off relay, such as 4, is now fully operated so that the common line relay 40 8 deenergizes to open the start circuit to the second link and when relay 10 is fully deenergized the start circuit for the first link is prepared at armature 12 and its resting contact. From the foregoing it will be seen that a two-relay allotter 45 has been provided for alternately taking the two links into use on successive calls.

Some provision should be made for taking into use an idle one of the links when the other is busy although the said other link is prepared 50 for seizure by the alternate two relay allotter. For example, it will be assumed that the first finder connector link shown in Fig. 2 is idle having been seized and released on a call of short duration subsequent to the call now maintaining 55 the second finder connector link busy. In this case in the two relay allotter relay 10 is locked in its energized position ready to seize the second link. Now if a call should be originated at this time relay 8 will energize as before to close 60 the start circuit. In this case since the second link is busy the start circuit therein is open at armature 145' or at the connector banks, with the result that neither the start relay 120' of the second link or relay 11 can energize. In this case 65 the start circuit now extends from grounded armature 9, armature 12 and its working contact, armature 15 since relay 11 is not energized, conductor 16, relay 120 of the first link and over the previously traced circuit to battery through 70 the connector motor magnet 135. This same condition also exists in case of open or dirty contacts in the start circuit. From the foregoing it will therefore be seen that the allotter seizes 75 the first link instead of the second link when the

first link is idle and the second busy at a time when the allotter has been set to normally allot the second link. The reverse of these conditions, that is, the allotter seizes the second link instead of the first link when the second link is idle and the first busy at a time when the allotter has been set to normally allot the first link, is also provided for and in such cases the relay 10 would be in normal position.

10 In case both the first and second links are busy the calling subscriber will not hear dial tone and will either wait until one of the links becomes idle or will replace the handset on the cradle.

15 Having described the invention, what is considered to be new and is desired to have protected by Letters Patent will be set forth in the following claims:

What is claimed is:

20 1. In a telephone system, a local exchange, a distant exchange, a trunk connecting said exchanges, a plurality of local subscribers' lines in said local exchange, a trunk connecting relay individual to each subscriber's line for connecting
25 such subscriber's line to said trunk line, subscriber controlled means for operating its individual trunk connecting relay to connect such subscriber's line to said trunk line in case said trunk line is idle, and a relay in said trunk operated in
30 case the trunk is busy for preventing the operation of any trunk connecting relay in response to the operation of said subscriber controlled means.

2. In a telephone system, a local exchange, a distant exchange, a trunk connecting said exchanges, a plurality of local subscribers' lines in said local exchange, a trunk connecting relay individual to each local line for connecting such subscriber's line to said trunk line, a circuit common to said trunk connecting relays over which said relays are energized, subscriber controlled means for completing said circuit to energize only its individual trunk connecting relay to connect such subscriber's line to said trunk line in case said trunk line is idle, and a relay individual to said trunk for opening said circuit when the trunk is busy to prevent the energization of any trunk connecting relay in response to the operation of said subscriber controlled means.

3. In a telephone system, a local exchange, a distant exchange, a trunk connecting said exchanges, a plurality of local subscribers' lines in said local exchange, a trunk connecting relay individual to each local line for connecting such subscriber's line to said trunk line, a circuit common to said trunk connecting relays over which said relays are energized, subscriber controlled means for completing said circuit to energize only its individual trunk connecting relay to connect such subscriber's line to said trunk line in case said trunk line is idle, a relay individual to said trunk for opening said circuit when the trunk is busy to prevent the energization of any trunk connecting relay in response to the operation of said subscriber controlled means, and a busy tone source controlled by said individual trunk relay connected to a subscriber's line in response to the operation of said subscriber controlled means when said trunk line is busy.

70 4. In a telephone system, a local exchange, a distant exchange, a trunk connecting said exchanges, a plurality of local subscribers' lines in said local exchange, a trunk connecting relay individual to each local line for connecting such subscriber's local line to said trunk line, a circuit
75 for each of said individual trunk connecting re-

lays, individual subscriber controlled means for completing the circuit to energize its individual trunk connecting relay to connect such subscriber's line to said trunk line in case said trunk line is idle, and a relay individual to said trunk line for opening said circuits when the trunk line is busy to prevent the energization of said trunk connecting relays in response to the operation of said subscriber controlled means.

5. In a telephone system, a local exchange, a local exchange, a trunk connecting said exchanges, a plurality of local subscribers' lines in said local exchange, a trunk connecting relay individual to each local subscriber's line for connecting such subscriber's line to said trunk line, 15 a circuit for each of said individual trunk connecting relays, each said circuit including a common portion individual to said trunk line, an operating potential normally connected to said common portion for producing current for energizing said trunk connecting relays, a busy tone source, a relay individual to said trunk line for disconnecting said operating potential from said common portion to prevent the energization of said trunk connecting relays and for connecting 20 said busy tone source to said common portion when said trunk line is busy, and individual subscriber controlled means for completing its individual circuit over said common portion and said operating potential to energize the subscriber's individual trunk connecting relay to connect such subscriber's line to said trunk line in case said trunk line is idle and for connecting said busy tone source to said subscriber's line over said common portion in case said trunk line is busy. 25 30

6. In a telephone system, a local exchange, a distant exchange, a plurality of trunk lines connecting said exchanges, a plurality of local subscribers' lines in said local exchange, a trunk connecting relay individual to each local line for connecting such subscriber's line to said trunk lines, a circuit for each of said individual trunk connecting relays, each circuit including a common portion individual to each of said trunk lines, an operating potential normally connected to said common portion at each trunk line for providing current for energizing said trunk connecting relays, a busy tone source, a relay individual to each trunk line for disconnecting said operating potential from said common portion at such trunk line to prevent the energization of said trunk connecting relays and for connecting said busy tone source to such common portion when such trunk line is busy, and individual subscriber controlled means for each trunk line for selectively connecting such subscriber's line to the trunk line corresponding to operated individual subscriber controlled means by completing the individual circuit to energize the individual trunk connecting relay over said operating potential and said common portion individual to such trunk line in case such trunk line is idle and for connecting said busy tone source to said subscriber's line over said common portion individual to such trunk line in case such trunk line is busy. 35 40 45 50 55 60 65 70 75 80 85

7. In a telephone system, a local exchange, a distant exchange, a plurality of trunk lines connecting said exchanges, a plurality of local subscribers' lines in said local exchange, a plurality of trunk connecting relays individual to each local subscriber's line for connecting such subscriber's line to said trunk lines, individual subscriber controlled means for each trunk line for selectively operating said trunk connecting relays to connect such subscriber's line to the trunk lines.

- line corresponding to the operated subscriber controlled means in case such trunk line is idle, and a relay individual to each trunk line operated in case the trunk line is busy for preventing the operation of one of said individual trunk connecting relays in response to the selective operation of any one of said individual subscriber controlled means in case said trunk line is busy.
10. 8. In a telephone system, a local exchange, a distant exchange, a trunk connecting said exchanges, a local subscriber's line in said local exchange having a local substation line loop, a trunk connecting relay individual to said subscriber's line, subscriber controlled trunk connecting means, an individual circuit for energizing said relay including contacts on said relay and said substation loop completed responsive to the operation of said trunk connecting means, and means including said contacts and said trunk connecting means for connecting said trunk line to said substation loop in response to the operation of said relay.
9. In a telephone system, a local exchange, a distant exchange, a trunk connecting said exchanges, a plurality of local subscribers' lines in said local exchange, each having a local substation line loop, a trunk connecting relay individual to each local subscriber's line, working contacts on each of said relays normally disconnecting said trunk line from said local subscribers' lines, an individual circuit for energizing each said relay, each circuit including resting contacts on its individual relay and the subscriber's local line loop, and subscriber controlled means for connecting said subscriber's local line loop to said resting contacts to energize its individual relay to connect said working contacts and trunk line to said subscriber's local line loop.
40. 10. In a telephone system, a local exchange, a distant exchange, a plurality of trunk lines connecting said exchanges, a local subscriber's line in said local exchange having a substation line loop, a trunk connecting relay individual to said subscriber's line, subscriber controlled trunk connecting means for each trunk line, an individual circuit for energizing said relay including contacts on said relay and said substation loop completed responsive to the operation of any one of said subscriber controlled trunk connecting means, and means including said contacts and the operated trunk connecting means for connecting the substation loop to the trunk line corresponding to the operated trunk connecting means in response to the operation of said relay.
11. In a telephone system, subscribers' lines, a pair of finders having access to said lines, a relay allotter for normally preselecting said finders alternatively regardless of their busy or idle conditions on successive calls, and means responsive to the initiation of a call on one of said lines in case the preselected finder is busy for operating said allotter to seize the other finder if idle.
12. In a telephone system, subscriber's lines, a pair of finders having access to said lines, a relay allotter for normally preselecting said finders alternatively on successive calls, means responsive to the initiation of a call on one of said lines for operating the preselected finder if idle to connect with the calling line, and means responsive to the initiation of a call on one of said lines in case the preselected finder is busy for operating said relay allotter to seize the other finder if idle and operate such finder to connect with the calling line.
13. In a telephone system, subscribers' lines, a pair of finders having access to said lines, a relay allotter for preselecting said finders, means responsive to the initiation of a call on one of said lines for operating the preselected finder if idle to connect with the calling line, means responsive to said connection for operating said allotter to preselect the alternate finder regardless of its busy or idle condition, means responsive to the initiation of another call by another one of said lines for operating the preselected alternate finder if idle to connect with this calling line, means responsive to this last connection for operating said allotter to preselect the first finder regardless of its busy or idle condition, means for releasing the alternate finder after conversation, and means responsive to the initiation of a third call by any one of said lines for operating the relay allotter to seize the alternate finder if idle and to operate it to connect with the calling line in case the preselected first finder is still busy in said first connection.
14. In a telephone system wherein a plurality of subscribers' lines are each provided with a trunk key for originating and answering trunk calls over a trunk line connected to a distant exchange, a trunk connecting relay individual to each subscriber's line; means enabling the operation of such relay in response to the operation of its individual trunk key only if said trunk line is idle, for connecting said trunk line to such subscriber's line; means for holding a trunk call while such subscriber completes a local connection to another local subscriber's line, and means responsive to the completion of said local connection for operating the trunk connecting relay individual to said other subscriber's line while said trunk is being held.
15. In a telephone system wherein a plurality of subscribers' lines are each provided with a trunk key for originating or answering trunk calls over a trunk line connected to a distant exchange, a trunk connecting relay individual to each subscriber's line operated in response to the operation of its individual trunk key in case said trunk line is idle and inoperative in response to the operation of said trunk key in case said trunk line is busy, each relay when operated connecting said trunk line to the subscriber's corresponding trunk key, means for holding a trunk call while a subscriber completes a local connection to another subscriber's line, and means responsive to the completion of said local connection for operating the trunk connecting relay individual to said other subscriber's line.
16. In a telephone system wherein a plurality of subscribers' lines are each provided with a trunk key for originating or answering trunk calls over a trunk line connected to a distant exchange, a trunk connecting relay individual to each subscriber's line operated in response to the operation of its individual trunk key in case said trunk line is idle and inoperative in response to the operation of said trunk key in case said trunk line is busy, each relay when operated connecting said trunk line to the subscriber's corresponding trunk key, means for holding a trunk call while a subscriber completes a local connection to another subscriber's line, means responsive to the completion of said local connection for operating the trunk connecting relay individual to said other subscriber's line, and means thereafter responsive to the operation of the trunk key individual to said other subscriber's line.

scriber's line for connecting said other subscriber's line to said trunk line.

17. In a telephone system wherein a plurality of subscribers' lines are each provided with a plurality of trunk keys for originating and answering trunk calls over a plurality of trunk lines connected to a distant exchange, a trunk connecting relay individual to each subscriber's line operated in response to the operation of any one of individual trunk keys if the trunk line corresponding to the operated trunk key is idle for connecting such trunk line to such subscriber's line, means for holding a trunk call while a subscriber completes a local connection to another local subscriber's line, and means responsive to the completion of said local connection for operating the trunk connecting relay individual to said other subscriber's line.

18. In a telephone system wherein a plurality of subscribers' lines are each provided with a plurality of trunk keys for originating and answering trunk calls over a plurality of trunk lines connected to a distant exchange, a trunk connecting relay individual to each subscriber's line operated in response to the operation of any one of said individual trunk keys if the trunk line corresponding to the operated trunk key is idle for connecting such trunk line to such subscriber's line, means for holding a trunk call while a subscriber completes a local connection to another local subscriber's line, and means responsive to the completion of said local connection for operating the trunk connecting relay individual to said other subscriber's line.

19. In a telephone system wherein a subscriber's line is provided with a plurality of trunk keys for originating and answering trunk calls over a plurality of trunk lines connected to a distant exchange, a trunk connecting relay individual to said subscriber's line, means for operating said relay in response to the operation of any one of said individual trunk keys if the trunk line corresponding to the operated trunk keys is idle for connecting such trunk line to said subscriber's line, and means for rendering said relay inoperative to connect said trunk line with said subscriber's line in response to the operation of said trunk key in case the trunk line corresponding to the operated trunk key is busy.

20. In a telephone system wherein a plurality of subscribers' lines are each provided with a plurality of trunk keys for originating and answering trunk calls over a plurality of trunk lines connected to a distant exchange, a first and a

second trunk connecting relay individual to each subscriber's line, means for operating the first of said trunk connecting relays only in response to the operation of a particular one of said individual subscriber's trunk keys to select the corresponding particular trunk line and prepare it for connection with such subscriber's line, means for operating the second of said trunk connecting relays in response to the operation of said particular key or any other individual trunk connecting key only in case the trunk line corresponding to the operated trunk key is idle for connecting such subscriber's line to the trunk line corresponding to the trunk key operated, means for holding a trunk call while the subscriber completes a local connection to another local subscriber's line, and means responsive to the completion of said local connection for operating the corresponding trunk connecting relays individual to said other subscriber's line.

21. In a telephone system, a local exchange, a distant exchange, a trunk connecting said exchanges, a plurality of local subscribers' lines in said local exchange, means for completing local connections between local subscribers' lines independently of said trunk line, a trunk connecting relay individual to each subscriber's line for connecting such subscriber's line to said trunk line, subscriber controlled means for operating its individual trunk connecting relay to connect such subscriber's line to said trunk line in case said trunk line is idle, and a relay in said trunk operated in case the trunk is busy for preventing the operation of any trunk connecting relay in response to the operation of said subscriber controlled means.

22. In a telephone system, a local exchange, a plurality of individual local subscribers' lines in said local exchange, subscribers' substation circuits normally connected to their individual lines, means for completing local connections between local subscribers' substation circuits over their individual lines, a distant exchange, a trunk connecting said exchanges, a trunk connecting relay individual to each subscriber's substation circuit for connecting such subscriber's substation circuit to said trunk line, subscriber controlled means for disconnecting the subscriber's substation circuit from its individual line and for operating its individual trunk connecting relay to connect such subscriber's substation circuit to said trunk in case the trunk is idle, and a relay in said trunk operated in case the trunk is busy for preventing the operation of any trunk connecting relay in response to the operation of said subscriber controlled means.

JOHN H. VOSS.
HARRY N. NEWSTEDT.
